DESIGN.

L. K. SMEDES.

CASKET.

No. 16,463.

Patented Jan. 12, 1886.

UNITED STATES PATENT OFFICE.

LEVI K. SMEDES, OF MOUNT VERNON, NEW YORK.

DESIGN FOR A CASKET.

SPECIFICATION forming part of Design No. 16,463, dated January 12, 1886.

Application filed October 29, 1885. Serial No. 181,335. Term of patent 14 years.

To all whom it may concern:

Be it known that I, LEVI K. SMEDES, a citizen of the United States, residing at Mount Vernon, in the county of Westchester and State 5 of New York, have invented and produced a new and original Design for Caskets, of which the following is a specification, reference being had to the accompanying drawings, forming part thereof.

10 This design relates to burial-caskets; and its characteristic features consist of a casket having its head and foot bounded by polygonal surfaces, so that each end of the casket includes the sides of a regular decagon, and provided with concave sides and ends formed by 15 molding-strips and inwardly-inclined panels.

In the accompanying drawings, Figure 1 is a perspective view of my newly-designed casket, showing the cover open. Fig. 2 is a similar view thereof, showing the cover closed.

20 Similar letters indicate corresponding parts. In the drawings, the letter A designates the body of the casket, and B is the cover thereof. The head and foot of the casket are bounded by polygonal surfaces formed by intersecting surfaces *a b c*, &c., the number of which latter may be varied as desired; but in the example shown in the drawings each end of the casket includes five sides of a regular decagon. The ends of the cover B are made to 25 correspond in their formation to the ends of

the body of the casket. The polygonal ends of the casket, as well as the sides D, are concave to the vertical plane, whereby the artistic effect of the casket is heightened. Around the 35 sides and ends of the body of the casket extend molding-strips E E', which are situated close to the bottom and top edge of the same, and inwardly-inclined panels F F' extend toward each other from the molding-strips E E', 40 thereby forming the concavity of the sides and ends. An intermediate molding-strip or plain flat strip, G, is placed midway between the molding-strips E E' and extends around the casket.

45 What I claim as new, and desire to secure by Letters Patent, is—

The design for a burial-casket, consisting of the body having its head and foot bounded by polygonal surfaces, and provided with the top 50 and bottom molding-strips, E E', the top and bottom inwardly-inclined panels, F F', and the continuous flat strip G, interposed between the inclined panels, substantially as shown and described.

55 In testimony whereof I have hereunto set my hand and seal in the presence of two subscribing witnesses.

LEVI K. SMEDES. [L. S.]
